UNITED STATES PATENT OFFICE.

PAUL A. NEHRING, OF SYCAMORE, ILLINOIS.

INSULATED-WIRE-SATURATING MACHINE.

1,168,542.

Specification of Letters Patent.

Patented Jan. 18, 1916.

Application filed August 7, 1914. Serial No. 855,690.

To all whom it may concern:

Be it known that I, PAUL A. NEHRING, a citizen of the United States, residing in Sycamore, in the county of DeKalb, in the State of Illinois, have invented new and useful Improvements in Insulated-Wire-Saturating Machines, of which the following is a specification.

This invention relates to insulated wire saturating machines and its principal object is to provide a machine of this class of novel and improved construction. Machines of this class are employed for the purpose of saturating the woven covering of insulated wire, with a suitable compound to provide an insulating substance around the metal wire for protection against the inclemencies of the weather.

Another object of this invention is to provide means for passing a continuous strand of insulated wire through a bath comprising a suitable compound, and maintaining it in said bath for a comparatively long time, although keeping it in continuous motion through the bath, and at the same time preventing the wire from piling upon itself and thereby preventing thorough saturation at the places where the wires might cross each other.

Another object is to provide a machine wherein a plurality of separate insulated wires may be saturated at one and the same time and with different kinds of wire saturating compounds.

The invention consists in the several novel features hereinafter fully set forth and claimed.

The invention is illustrated in the accompanying drawings in which:

Figure 1 is a side elevation of a machine embodying a simple form of the present invention, part of the wall of the tank being broken away to illustrate parts within the tank; Fig. 2 is a plan thereof; Fig. 3 is a detail, vertical section taken on line 3-3 of Fig. 1; Fig. 4 is a detail side view of a strut and nuts which are employed in the construction of the dipping drums around which the wire is wrapped; Fig. 5 is a perspective view of a cam for actuating certain wire shifters; Fig. 6 is a side view of one of the wire shifters; Fig. 7 is a perspective view of a bearing block for the shaft of the drum; Fig. 8 is a perspective view of a housing for said bearing block; Fig. 9 is a perspective view of one member of a housing

or the bearing blocks located inside of the tank, and Fig. 10 is a perspective view of the tank alone.

Referring to said drawings, 12 designates a rectangular tank which may be divided into two separate compartments by a lengthwise extending, vertical wall or partition, 12^a, secured to the end walls of the tank. Each compartment is adapted to contain a suitable compound with which the insulated wire or wires is or are to be saturated.

Within each compartment are rotary, dipping drums, 13, two being here shown in each compartment, and said drums are mounted on drive shafts, 14, journaled in upright, bearing blocks, 15, which are supported in housings, 16, secured to the side walls of the tank and in housings, 10, secured to the partition, 12^a. In the form of 75 the invention illustrated the side walls, 12^b, are slotted vertically for the reception of the shafts, 14, and the housings, 16, are bolted to the outside of the side walls. Each housing, 16, has a recessed portion, 16^a, for the 80 reception of the bearing block, 15, and a bottom portion, 16^b, upon which said bearing block rests. The recessed portion faces the slot in the side wall so that the shaft may extend through said slot and into the bearing block.

The housings, 10, may each comprise two side members, 10^a, secured to the partition, 12^a, and having vertical angle-shaped parts, 10^b spaced apart to permit the shaft 90 to pass therebetween, and having bottom portions, 10^c, for the bearing block to rest on.

The drums, 13, are of open work construction and each may comprise two spaced disk-like sides, 21, having a hub fast on the shaft. Secured to and extending between each pair of disks near their peripheral edges, are struts, 22, which are arranged circumferentially around the drum, and spaced 95 comparatively close together. Said struts are arranged parallel with the drum shaft and form the open drum face of the drum. The insulated wire which is to be saturated, is wrapped around both drums in a compartment, and leads from one drum to the other; by making several turns around each drum a considerable length of wire may be 100 contained in the tank at any given time, and a thorough saturation of the wire may be 105 effected.

Each wire enters the tank through a

tubular wire guide, 26, secured to one end wall of the tank in line with the tops of the drums, and near one side thereof (see Figs. 1 and 2), and after being wrapped several 5 times around the adjacent or first drum, is then wrapped several times around the other drum and led through a wiper board, 27, secured on the other end wall; the wire finally passes out through a hole in said end 10 wall. To prevent the turns of wire from piling upon each other, means are provided for pushing the wire from the side of the drum at which it winds on to the drum, to that side from which it leaves, and a simple 15 form of means is shown. Preferably said means comprise a plurality of wire shifting arms, 24, carried by the drums and movable transversely of the drum face, and cams, 25, for effecting movement across said drum face 20 at least in one direction; said wire shifting arms are shown as extending radially of the drums, and pivoted to the inner faces of the sides, 21, thereof adjacent the wire guides, 26. Said arms project out through the drum 25 face—that is, between the struts, 22, and engage the incoming wire. The cams, 25, are shown as supported from the side walls and partition of the tank by brackets, 25^a. Each cam is in the form of an arc of a circle having the axis of the drum as a center, (see 30 Fig. 1), and it has a cam face arranged to engage the arms, 24, as they pass by it. Said cam face extends from a point nearest the incoming side of the tank and to one side of 35 the drum, to a point located over the face of the drum and then back to one side thereof, whereby each arm as it moves past the cam is engaged thereby and swung over sufficiently to shift the wire a distance equal to 40 or greater than the diameter of the wire. In the construction shown, the wire enters at points near the partition, leaves the first drum nearer the side wall, leads upon the second drum at a point near the side wall 45 and leads away therefrom at a point near the partition, consequently, the cams for the first drum are supported near the partition and, with the associated arms, 24, act to push the wire toward the side wall, whereas 50 the cams for the second drum are supported near the side wall and, with the associated arms, 24, act to push the wire toward the partition. This arrangement is not material, but has been chosen for the purpose 55 of illustrating the invention. After passing the cams, 25, the arms, 24, are moved back to their original position, and the means for accomplishing this result is here shown to comprise coiled, compression springs, 24^b, 60 interposed between the arms, 24, and opposite side, 21, of the drums, said springs being carried by rods, 24^c, secured to the sides, 21, of the drums.

The driving mechanism for the drums 65 may conveniently comprise gear wheels, 19,

secured to the drums or their shafts, 14, pinions, 20, meshing with said gear wheels and mounted upon shafts, 17, journaled in bearing boxes, 18, secured to the side walls and partition of the tank. Said shafts, 17, 70 extend beyond the side walls and have sprocket wheels, 29, mounted thereon and sprocket chains, 30, are trained around the sprocket wheels as shown. Power may be applied in any suitable manner, and I have 75 shown belt pulleys, 28, on the shafts, 17, at one end of the tank which may be belted to any suitable drive pulleys.

In use either or both tanks, as the case may be, are partially filled with insulating 80 compound and the initial ends of the insulated wire threaded through the wire guide, 26, wrapped around the first drum a number of times, then around the other drum, past the wiper board and led out through the end 85 wall of the tank. Power being applied to the pulley, 28, the drums are revolved slowly, thereby winding on undipped wire and unwinding the dipped or saturated wire which is taken up in any suitable manner. 90 As the wire shifting arms pass the cams, they are moved over, thereby pushing or shifting the adjacent portions of the wire over toward the other sides of the drums, and as the arms leave, the cams are returned 95 to normal position by the springs. During a complete revolution of a drum all of the wire thereon is thus shifted over to make room for the incoming wire, thus preventing it from piling up on the drum face. 100

I realize that various alterations and modifications of the exact construction shown and described, are possible without departing from my invention, and I desire, therefore, not to limit myself to the exact 105 form of the invention shown and described, but intend in the following claims to point out all of the invention disclosed herein.

I claim as new and desire to secure by Letters Patent:

1. In a wire saturating machine, a compound containing tank having an upright slot in its side wall, an upright housing secured on the outside of said wall and covering said slot, an elongated bearing block 115 mounted in said housing and vertically movable therein, a shaft, one end of which is journaled in said bearing block, and an insulated wire dipping drum mounted on said shaft.

2. In a wire saturating machine, a compound receiving tank, a rotary wire dipping drum journaled therein, wire shifting members carried by said drum and having portions extending through the drum face, and 125 a stationarily supported cam co-operating with said wire shifting members to move them crosswise of the drum face.

3. In a wire saturating machine, a compound receiving tank, a rotary wire dipping 130

drum journaled therein, and having an open work drum face, a plurality of wire shifting members carried by said drum and having portions projecting beyond and movable across the drum face, and a cam supported by the tank and lying in the path of movement of said wire shifting members, said cam having a cam face concentric with the axis of rotation of said drum and running from one side of the drum toward the other and back.

4. In a wire saturating machine, a compound receiving tank, a rotary wire dipping drum journaled thereon and having a drum face comprising a plurality of circumferentially arranged transverse struts, a plurality of wire shifting arms having portions projecting between the struts and movable transversely of the drum face, and means for actuating said wire shifting members.

5. In a wire saturating machine, a compound receiving tank, a rotary wire dipping drum journaled therein and having a drum face comprising a plurality of circumferentially arranged transverse struts, a plurality of wire shifting arms having portions projecting between the struts and movable transversely of the drum face, a stationarily supported cam having a cam face concentric with respect to the axis of rotation of said drum and acting to move said wire shifting members in one direction across the face of the drum, and springs bearing against the wire shifting arms and acting to move them in the opposite direction.

25 6. In a wire saturating machine, a com-

pound receiving tank, a rotary wire dipping drum journaled therein and having a drum face comprising a plurality of circumferentially arranged transverse struts, a plurality of wire shifting arms pivoted to said drum and having portions projecting out between said struts, and movable transversely of the drum, springs carried by the drum and bearing against said wire shifting arms for moving them in one direction and a cam supported by the tank, and lying in the path of movement of said wire shifting arms and arranged to move them in the opposite direction.

7. In a wire saturating machine, a compound containing tank, two wire dipping drums journaled therein, and in horizontal alinement with each other, wire shifting members carried by both drums and having portions projecting out through the drum faces, and stationarily supported cams lying in the path of movement of said wire shifting members and acting to move them transversely of the drum faces, the wire shifting members and cam associated with one drum, being located at one side thereof, and those of the other drum being located at the opposite side thereof, substantially as and for the purpose specified.

In witness whereof, I have hereunto signed my name, at Sycamore, Dekalb county, Illinois, this third day of July 1914.

PAUL A. NEHRING.
